UNITED STATES PATENT OFFICE.

FRANK M. WRIGHT, OF LYONS, NEW YORK.

CAN-FILLING MACHINE.

1,151,146.

Specification of Letters Patent. Patented Aug. 24, 1915.

Application filed May 21, 1913. Serial No. 769,106.

To all whom it may concern:

Be it known that I, FRANK M. WRIGHT, a citizen of the United States, residing at Lyons, in the county of Wayne and State of New York, have invented certain new and useful Improvements in Can-Filling Machines, of which the following is a specification, reference being had to the accompanying drawings.

This invention comprehends certain new and useful improvements in can filling machines and has for its primary object to provide a machine which will be constructed in such manner as to be especially adapted for filling open top cans with sauer kraut and the like.

Another object is to provide a machine of this character which will be provided with mechanism for receiving, righting and feeding cans from a chute to a vertically movable plate to be raised to a spout or funnel and receive the sauer kraut or other products from a feeding hopper.

Another object is to provide a machine of this character which may be provided with means for automatically opening and closing a cut off valve within the spout or funnel as the cans are engaged with and disengaged from said spout or funnel.

Another object is to provide a machine of this character which will be constructed in such manner that operation of the can feeding mechanism will be discontinued during the operation of filling the cans and again operated after the filling of each can until the succeeding can is delivered to the plate and raised into engagement with the spout or funnel.

Another object is to provide a machine of this character which will be provided with a plurality of can feeding chutes, can conducting belts, etc., and an equalizer bar connected with each can receiving and raising plate or table and having a weight adjustably mounted thereon for regulating the amount of sauer kraut or other products or materials to be packed in each can.

A further object is to provide a machine of this character which will be of such construction that the receiving hopper above each filling hopper will be divided into two compartments with a screw extending transversely beneath the two compartments for feeding the sauer kraut from the receiving hopper to the intermediate hopper from which it is fed to the feeding hopper carry-

ing the filling spout or funnel and a return screw beneath the second compartment of the receiving or uppermost hopper for preventing over-feeding of sauer kraut to the intermediate or second hopper and thereby interfering with the proper operation of the radial plates upon the rotary shaft in said intermediate or second hopper for depositing the sauer kraut upon the feed worm within the feed hopper.

A further object is to generally improve and simplify the construction and operation of machines of this character and provide electrical connections between certain operative parts of the device and generally increase the efficiency and value of the machine.

With the above and other objects in view, this invention consists in the novel features of construction, combination and arrangement of parts to be hereinafter more fully described, claimed and illustrated in the accompanying drawings, in which—

Figure 1 is a side elevational view of the complete device; Fig. 2 is a view similar to Fig. 1, looking at the opposite side of the machine, parts of the machine being broken away in this view for the sake of clearness; Fig. 3 is a rear elevational view of the complete machine; Fig. 4 is a detail vertical cross-sectional view on the line 4—4 of Fig. 1 looking in the direction indicated by the arrow; Fig. 5 is a top plan view of the uppermost hopper and parts carried thereby; Fig. 6 is an enlarged detail cross-sectional view through the main frame member and can conveying chain with a can in position upon the chain with a portion of the can broken away, said view showing in elevation the rear end of the equalizer bar in position in its guide member also clearly illustrating the means for retaining the equalizer bar in its uppermost position and the electrical contact members carried by the equalizer bar and guide member; Fig. 7 is a fragmentary detail view of the equalizer bar; Fig. 8 is a fragmentary top plan view of the same and the poise or weight carried thereby; Fig. 9 is a detail cross-sectional view on the line 9—9 of Fig. 8; Fig. 10 is a detail view partly in section of the slide valve for the lower end of one of the spouts and the mechanism for operating the slide bar, said view also showing in dotted lines a can in position to be filled, the valve being shown in this view in open position; Fig. 11 is a detail

top plan view of the trigger bars in normal position, said view also showing the parts connected with one of the trigger bars and a can just past said bars; Fig. 12 is a detail 5 elevational view of the clutch and mechanism for operating the same to throw into operation the mechanism for moving the chain after a can has been filled and said filled can and table returned to their lower- 10 most position; Fig. 13 is a detail view of the star-shaped can separating and raising wheel, showing in dotted lines a can in each of the longitudinal grooves of said wheel, the shaft of said wheel shown in cross-section; Fig. 14 is a detail view of one of the 15 can righting wheels, showing the shaft of the same in cross-section; Fig. 15 is a detail elevational view of the maltese cross wheel and geneva gear for operating the sprocket 20 chain which imparts intermittent rotary movement to the turret shaft; Fig. 16 is a fragmentary detail view showing the gearing and clutch for operating the feed and return screws positioned in the bottom of the 25 first or uppermost hopper; Fig. 17 is a longitudinal sectional view through the rotary slidable sleeve and the spaced shafts for operating the can separating and raising wheel connected thereby; Fig. 18 is an elevational 30 view of the parts shown in Fig. 17; Fig. 19 is a top plan view of the can raising table; Fig. 20 is an end elevational view thereof; Fig. 21 is a side elevational view thereof with a portion of the depending member 35 carried by the table broken away; and Fig. 22 is a detail plan view showing the shafts upon which the can separating and raising wheel and the can righting wheels are mounted, said view showing the operative 40 connections between these shafts. Fig. 23 is a detail sectional view on the line 23—23 of Fig. 10; and Fig. 24 is a detail plan view of the extended end of the turret shaft and gears carried upon the same. Figs. 25 and 45 26 are fragmentary detail views of certain parts of the operating mechanism.

Referring more specifically to the drawings in which similar reference characters designate corresponding parts throughout 50 the several views, 1 designates the receiving or uppermost hopper, which is divided into two compartments designated by the numerals 2 and 3 separated by the longitudinal vertical partition 4. Extending transversely beneath the compartments 2 and 3 and the partition 4 of the hopper 1, is a trough 5 within which is positioned the feed screw 6, the shaft 7 of which extends through the opposite ends of the trough 5. It will be 55 understood that the trough 5 is located near the front edge of the lower portion of the hopper while a second trough 8 is formed under the hopper 1, adjacent the rear edge of said hopper, the bottom of the portion of the trough 8 beneath the compartment 2,

being inclined toward the outer side of said compartment, the purpose of which will presently be apparent.

Within the portion of the trough 8 beneath the compartment 3, however, is positioned the return screw 9 which has the ends of its shaft 10 mounted in the partition 4 and the outer side wall of the compartment 3. The shafts 7 and 10 are parallel to one another and it will be understood that the 75 partition 4 is cut away below the shaft 10 and also suitably cut away above the trough 5 to accommodate the feed screw 6 and allow said feed screw to feed the sauer kraut or other product placed in the compartment 80 2 to the compartment 3. The return screw 9 serves to return the sauer kraut or other products to the compartment 2, should an over amount be fed to the compartment 3 by the feed screw 6, thereby eliminating all 85 danger of choking the intermediate hopper 11.

The intermediate hopper 11 is positioned immediately beneath the second compartment 3 of the hopper 1 and is provided with 90 flat vertical side walls and outwardly curved front and rear walls, as clearly shown in the drawings. Extending centrally and transversely through the intermediate hopper 11 is a shaft 12 upon which are mounted radi- 95 ally extending plates 13 upon which is deposited the sauer kraut or other product from the feed screw 6 and which in turn deposits the sauer kraut in the lower or feed hopper 14 and upon the feed worms 15 100 in the inclined bottom portion of said lower or feed hopper 14.

It will be understood that the portion of the trough 5 beneath the compartments 2 and 3 of the hopper 1 opens into the intermediate hopper 11 while the trough 8 is provided with an open bottom beneath the compartment 3 and the solid inclined bottom beneath the compartment 2 of said hopper 1. The lower or feed hopper 14 is provided 110 with flat vertical sides and an inclined hinged back 14' forming a continuation of the curved back of the intermediate hopper 11, while the front of the hopper is vertical and extends a short distance downwardly, as 115 shown at 16 and connects with the upper end of the inclined bottom 17 of said lower or feed hopper. The object of having the back 14' hinged is to permit access to be had to the hopper should the same become 120 clogged, or for the purpose of cleansing.

The feed spouts or funnels 18 extend downwardly from the lower ends of the inclined bottom 17 and the front and sides of the hopper, said spouts or funnels therefore 125 being at the lowermost portion of the hopper 14. It will also be seen that the lower ends of the feed worms 15 project into the spouts or funnels 18, said worms being formed upon the shafts 19 which have their 130

lower ends rotatably mounted through the front portions of the spouts 18 while their upper ends are similarly mounted through the back of the wall 16 of the hopper 14 and have the worm wheels 20 mounted upon their upper extremities and engaged by the worm gears 21 and operated by the latter, each worm gear 21 being carried upon the upper end of a vertical shaft 22 which has a friction wheel 23 mounted upon its lower end.

Each spout or funnel 18 has a reduced circular lower edge 24 for engagement within the upper end of each can 25 during the operation of filling the same, the can being automatically raised and its upper end engaged around said lower circular edge 24 of the spout or funnel 18, by means of the novel and improved mechanism which will be later fully described.

The spout or funnel 18 is normally closed by the cut off valve 26 which is slidably engaged through the lower portion of said spout or funnel and which has the upwardly extending lug 27 formed upon its outer extremity and the upwardly and forwardly directed arm 28 inwardly of said extremity, the forwardly directed portion of said arm being directed toward the outer extremity of the cut off valve, which it will be understood is in the form of a flat plate or strip having its rear end slidably engaged through the spout or funnel 18, as previously mentioned. The cut off valve 26 is opened and closed by means of the reciprocating latch dog 29 connected to the cam wheel 30 upon the shaft 31 which is continually in rotation.

The latch dog 29 is normally retained in raised position and out of engagement with the lug 27 by means of the pony jack 32, it being understood that the free extremity of the arm 28 is in a horizontal plane above the horizontal plane of the lug 27. The pony jack 32 is held in normal position by means of the coil spring 33 and said pony jack has an operating rod 34 connected therewith and with the trigger bar 35 whereby the pony jack 32 will be operated upon operation of said trigger bar in one direction to allow the free end of the latch dog 29 to drop downwardly and engage the lug 27 and thereby draw the cut off valve 26 forwardly to open the same and allow the sauer kraut or other product to be forced from the spout or funnel 18 into the can 25 engaged therewith. It will be understood that the pony jack 32 is locked in this position by means of the spring latch 182 carried upon the support 190, as shown at 183.

Immediately after the can has been filled and returned to its lowermost position with the table, thereby returning the equalizer bar 40 to its uppermost position, engaging the contact plates 58 and 60, and completing a circuit, the electric current will pass through the wires 186 causing the magnet 185 to at-

tract the lateral arm 184 of the spring latch 182 and thereby draw the free end of the spring latch 182 rearwardly to allow the spring 33 to return the pony jack 32 to normal position, said spring 33 being carried in the socket 192 connected to the support 190, thereby raising the reciprocating latch dog 29 and causing the same to strike the forwardly directed arm 28 of the cut off valve and force the same inwardly, closing the spout 18. The chain 50 will again be brought into operation to draw the filled can from upon the table and bring the next can into position. It will be understood that owing to the fact that the pony jack 32 is connected with the trigger bar 35 by means of the rod 34, said trigger bar will be returned to its normal position upon the return of the pony jack to its normal position to be again operated upon outward movement of the trigger bar as the next can passes between the trigger bars 35 and 70, said pony jack riding over the spring latch 182 until it catches back of the same, where it will be held until again released as before described.

It will be understood that the lower or feed hopper 14 is provided with a plurality of feed worms 15 and in the present instance I have shown four such worms and a corresponding number of spouts or funnels 18. It will further be evident that a cut off valve 26 and means for operating the same must be provided for each spout or funnel and a can receiving and raising plate or table 36 positioned beneath each spout or funnel 18. A rod 37 is also connected at one end to the trigger bar 35 and has its opposite end engaged against the equalizer latch carrying bar 38 which has the equalizer latch member 39 mounted thereon for supporting the free end of the horizontal arm of the equalizer bar 40 in its uppermost position, upon which arm is adjustably mounted the poise or weight 41. The vertical arm of the equalizer bar 40 depends from the opposite end of the horizontal arm and extends slightly forwardly and the equalizer bar is mounted at the junction of its arms upon the shaft 43, a suitable opening being provided at this point, as shown at 42, to accommodate the shaft. It will be understood that the shaft 43 is loosely mounted in the bracket member 52 and extends transversely therethrough. It will be understood that the vertical arm of the equalizer bar 40 is mounted upon the pin 44 in one end of the slide rod 45, said pin being carried in the rear end of the rod 45 sliding in the pivotally supported bracket arm 45', the opposite end of the rod 45 being provided with an elongated longitudinal slot 45'' through which is engaged the pivot pin 46' mounted transversely in the lower end of the table raising post 46 which has its upper end secured to 130

the under face of the table 36. As herein embodied, the bracket arm 45' is pivotally engaged, as at 45", with the arm 45^b depending from the frame member 49. As is believed to be self-evident, downward movement imparted to the post 46 under the influence of the weight of a can positioned on the table 36 will impart such rocking movement to the rod 45 about the pivot 45" 10 as to elevate the long or horizontal arm of the equalizer bar 40. Upon removal of the weighted can from the table 6, the table will be returned to its uppermost position under the influence of the poise or weight 41, in a manner which is believed to be self-evident.

The can receiving and raising table 36 is provided in its upper face with a deep longitudinal channel 36' to accommodate the chain 50, as will be later clearly understood. 20 The table 36 is also provided with outwardly directed flanges 36" at its upper opposite side edges and with the vertical spaced ribs 36'", formed upon its sides beneath the flanges 36". It will be understood that a 25 suitable recess 48 is provided in the main frame member 49 and that bearing balls 47 are preferably provided in said recess, for engagement by the ribs 36'" in order to reduce friction to the minimum upon vertical movement of the table. The main frame member 49 is also provided with a recess 51 extending longitudinally therethrough to accommodate the chain 50, as will be readily understood. The chain 50 is engaged over 30 the sprocket wheels 52 and 53 at opposite ends of the main frame member and mounted in suitable brackets secured to the under face of said frame member, it being understood that the sprocket wheels 52 and 53 are 35 carried upon the transverse shafts 54 and 55, respectively. The sprocket chain 50 has the laterally directed can engaging fingers 56 upon its outer or upper face and at spaced distances for engaging cans 25 and retaining 40 the same in position as they are moved by the chain 50. The main frame member 49 is mounted upon suitable standards 57 which have their lower ends resting upon 45 the floor or other stationary support. It will be apparent that the main frame member 49 may be formed of any suitable material and may be of any suitable length.

It will be understood that the equalizer bar 40 has the contact plates 58 and 59 upon 50 its upper and lower faces at the free end of its horizontal arm for engagement with the contact plates 60 and 61, respectively, to complete different circuits when the equalizer bar is in its uppermost position and 55 lowermost position. The purpose of arranging the contact plates as just described is to complete electrical circuits and cause proper operation of other parts of the machine at the proper time, as will be later 60 clearly apparent. It will further be seen

that the contact plate 60 is secured in the upper end of the U-shaped guide member 38' while the contact plate 61 is carried at a lower point in said bar or guide 38', the contact plates 60 and 61 being positioned 70 at the opposite ends of the elongated slot through which the end of the long arm of the equalizer bar 40 is engaged. The U-shaped guide members 38' has a depending portion 62 at its lower end through which 75 bolts 63 or other suitable securing means are engaged for securing the U-shaped guide member 38' to the side of the frame member. The latch member 38 is in the form of a bar which is normally in vertical position and is fulcrumed to the rear face of the U-shaped guide member 38', as shown at 64, and has the latch lug 39 near its upper end for engagement against the under face of the long arm of the equalizer bar 40 to 80 retain the same in its uppermost position. The latch bar 38 has a slightly curved lower end 66 which is normally held partly over the opening through the ear 67 projecting outwardly from the side of the U-shaped 85 guide member 38', by means of the coil spring 68 which has one end secured to the curved lower end of the latch bar 38 while its opposite end is secured to a suitable lug 69 upon the rear face of the lower end of 90 the U-shaped guide member 38'. The latch bar 38 is adapted to be swung upon its fulcrum 64 by means of the rear free end of the rod 37, previously mentioned, extended through the perforated ear 67 when the rod 100 37, which has its opposite end connected with the trigger bar 35, is swung in said ear by outward movement of the trigger bar thereby withdrawing the lug 39 of the latch bar 38 from beneath the equalizer bar 40 and 105 allowing said bar to drop to its lowermost position.

It will be understood that a second trigger bar 70 is positioned opposite the trigger bar 35 and turns in the bearing 71 provided 110 therefor. The lower end of the trigger bar 70 is turned outwardly at about right angles, as shown at 72, and connected with one end of the longitudinally extending spring 73' which has its other end connected to the 115 lug 74 projecting laterally from the main frame member 49 near the lower end of the trigger bar. The sleeve 75 carries a clutch lever engaging projection 76 near its lower end and said sleeve is adapted for partial 120 rotation around the stationary rod 77 and upon turning of said sleeve 75 by the forward movement of the bar 73, the clutch lever engaging member 76 will engage against the clutch lever 78 and swing the 125 same upon its pivot 79 against the tension of the clutch lever spring 80 and thereby disengage the clutch member 81, carried upon the lower end of the lever 78 and slidably mounted upon the shaft 82, from the 130

clutch member 83 carried by the friction drive wheel 84, which latter is loosely mounted on one end of the shaft 82 and has the friction wheel 85 engaged therewith. 5 The friction wheel 85 is mounted upon the lower end of the inclined shaft 86 which has the drive worm 87 formed upon its upper end and engaged with the worm wheel 88 rigidly mounted upon an extended end of 10 the shaft 55 to drive said shaft and thereby rotate the chain 50. It will be understood that the clutch member 81 is engaged with the clutch member 83.

It will be understood that the lateral arms 15 of the trigger bars 35 and 70 are directed forwardly and curved outwardly in opposite directions to receive therebetween, in regular order, the cans 25 and guide said cans to proper position upon the table 36. 20 It will also be understood that the trigger bar 35 has a vertical portion rotatably mounted in a suitable bracket 35' upon the side of the main frame member 49 opposite the side upon which the bearing 71 is secured and that the forward end of the rod 37 is secured to the main or curved portion 25 of the trigger bar, and to the lower end of the bar is secured one end of a suitable spring 35'' which has its opposite end secured to the main frame member 49 and 30 serves to resiliently retain the trigger bar 35 in normal position. As the trigger bar 70 is resiliently retained in normal position by means of the spring 73' connected with its lower end and with the main frame member 49, it will be understood that when the trigger bars 35 and 70 are in normal position, the space between the curved upper ends thereof will be less than the diameter 35 of the cans, thereby causing each can as it passes between the trigger bars to force the same outwardly and thereby operate the parts connected with the trigger bars to stop movement of the chain 50 and release 40 the equalizer bar 40 to allow the same to drop to its lowermost position and raise the table. 45

The gear wheel 89 is mounted upon one end of the shaft 82 and engaged with this gear wheel is a drive gear 90 mounted upon the drive shaft 91 operated by the belt leading from any suitable source of power. The shaft 82 is mounted in suitable bearings 92 upon the longitudinal supporting members 55 93 which are connected at their opposite ends to the standards 57 adjacent the lower ends of the latter. One end of the shaft 82 is extended and mounted in the upper end 92' of a suitable bracket bearing secured to 60 the floor or other stationary support. It will be understood that the shaft 82 extends transversely beneath the main frame member a spaced distance from the rear end of the same, while a similar shaft 94 is positioned parallel to the shaft 82 beneath the. 65

forward portion of the main frame member 49 and mounted in suitable brackets 95 carried upon the frame members 93. The friction wheel 23 is engaged against the large friction wheel 96 which is loosely mounted upon the shaft 94 and carries a clutch member 97. A second clutch member 98 is keyed to the shaft 94 and adapted for engagement with the clutch member 97 to lock said member 97 and friction wheel 96 for rotation with the shaft 94 to drive the friction wheel 23 and thereby rotate the vertical shaft 22 and cause the worm 21 engaged with the worm wheel 20 to revolve the latter and thereby operate the feed screw 15. 80 It will be understood that the clutch member 98 is engaged with the clutch member 97 by turning the clutch lever 99 upon its fulcrum 100 and against the tension of its spring 101, by engaging the clutch lever engaging member 102 with the upper end of said lever 99. The member 102 is carried by the sleeve 103 which is rotatably mounted upon the stationary rod 104 and has a laterally projecting arm 105 to which is pivoted 90 one end of a rod 106, as shown at 107. Electrical connections are formed between the opposite end of the rod 106 and the lower electrical contact plate 61 and a circuit is completed when the equalizer bar 40 95 drops to its lowermost position and the contact plate 59 carried thereby engages with the contact plate 61, thereby drawing the rod 106 rearwardly and rotating the sleeve 103 sufficiently to cause the lever engaging 100 member 102 to swing the lever 99 upon its fulcrum 100, as will be clearly understood. It will therefore be seen that the clutch member 98 will be engaged with the clutch member 97 to operate the feed screw 15 after 105 a can has been engaged with the lower end of the spout 18 and the valve 28 has been opened. It will also be understood that after the can 25 has been filled and the weight of the material within the same 110 causes the can to move downwardly and return the table 36 to its normal position, thereby overcoming the weight of the equalizer bar 40 and poised 41 upon the same and returning the equalizer bar to its normal 115 position, the contact plate 58 carried by the equalizer bar 40 will engage with the contact plate 60 at the upper end of the U-shaped guide member 38' and thereby complete a circuit to draw the spring latch 182 120 to inoperative position and thereby allow the pony jack and parts connected therewith to return to normal position and close the valve 26.

The return of the equalizer bar to its uppermost position and engagement of the contact plate 58 with the contact plate 60 completes the circuit within which is positioned the magnet 177, causing the latter to draw the rod 78 forwardly thereby turning the 130

sleeve 75 against the tension of the spring 75' and causing the clutch lever engaging projection 76 to engage with the clutch lever 78 causing the same to engage the clutch member 81 with the clutch member 83 to cause the chain 50 to again move to carry the filled can from upon the table 36 and bring the next can into position to be filled in like manner. It will also be understood that as the free end of the equalizer bar moves upwardly the contact plate 59 will disengage from the contact plate 61 and allow the spring 101 to return the rod 106 and sleeve 103 and parts connected with the latter to normal position and thereby permit the spring 101 to swing the lever 99 upon its fulcrum 100 and disengage the clutch member 98 from the clutch member 97 and thereby discontinue operation of the feed screw 15 until the next can 25 is in position to be filled and the valve 26 is again in open position, as will be readily apparent. It will also be understood that the transverse shaft 94 is operated from the transverse shaft 82 by means of the longitudinal shaft 108 having the bevel gear 109 upon one end and engaged with the double bevel gear 110 carried upon the end of the shaft 82 opposite the gear wheel 89 while a bevel gear 111 is upon the opposite end of the shaft 108 and engaged with the bevel gear 112 upon the corresponding end of the shaft 94.

Engaged with the other face of the double bevel gear 110 is a bevel gear 113 upon the lower end of the long inclined shaft 114 which has a second bevel gear 115 upon its upper end and engaged with the bevel gear 116 mounted upon one end of the shaft 7 upon which the screw 6 is carried. The shaft 7 also has loosely mounted upon this end, a gear wheel 117 having the grooved collar 118 carried thereby having the lever 119 engaged in the groove thereof with an operating rod 120 connected with its free end and running the full width of the machine, by means of which the lever 119 may be readily operated to move the gear 117 longitudinally upon the shaft 7 to cause the teeth to engage with the teeth of the gear wheel 121 mounted upon the shaft 10 of the return screw 9 to operate said screw as occasion may require. It will be understood that co-operating clutch members 116' and 117' are carried by the bevel gear 116 and gear wheel 117 respectively, to cause the former to rotate the latter when the clutch members are engaged.

The turret shaft 12 has a sprocket wheel 122 mounted upon its extended end and engaged around this sprocket wheel is a sprocket chain 123 which is also engaged around the sprocket wheel 124 which is mounted upon a stub shaft 125 which also has mounted thereon a Maltese cross wheel 126 comprising a plurality of wide arms 127 with narrow slots

128 positioned therebetween, the outer ends of the arms 127 being concave, as shown at 128. The Geneva gear 129 is formed on the outer or flat face of the bevel gear wheel 112 and said cam member is positioned centrally upon the bevel gear 112 and has the shaft 94 projecting therethrough. The cam member 129 has a portion of its periphery concave, as shown at 129' by cutting away a portion of said member and the pin or finger 130 projects radially from the center of the concave portion 129' for engagement in each of the slots 128 in turn, as the Geneva gear rotates with the gearing 112 and shaft 94, rotating the Maltese cross one-fourth of a revolution upon each revolution of the Geneva gearing, the convex portions of the latter turning in the concave outer ends of the arms 127 without having any effect on the Maltese cross, as will be clearly understood. It will therefore be seen that the turret 113 will be properly operated to deposit the sauer kraut or material upon the screws 15 and to return any excessive amount of material and present the same to the return screw 9 to be returned by the screw to the compartment 2 of the hopper 1, as previously stated.

The cans 25 are conveyed to the chain 50 from the chute 132 by novel mechanism which will now be described.

The lower portion of the long chute 132 is enlarged as shown at 133 and a shaft 134 is positioned transversely therethrough with the can lifting wheel 135 mounted thereon, said wheel having longitudinal grooves 136 formed in its face of proper size to receive one can and raise the same over the wheel as the latter rotates, thereby separating the cans and preventing more than one can being deposited upon the chain 50 at a time. The wheel 135 may be provided with any suitable number of can accommodating grooves but I have provided the wheel with four such grooves and it will be understood that the wheel is positioned in a horizontal portion of the chute 132 near its connection with the lower vertical end of chute which tapers toward its lower extremity and is of proper size to accommodate a can in upright position and prevent the same from turning upon its side. The lower portion of the chute is designated by the numeral 137. The shaft 134 has a pair of spaced bevel gears 138 mounted thereon at spaced distances from the opposite ends of the can separating and lifting wheel 135 and a pair of parallel shafts 139 extended at right angles to the shaft 134 and having the bevel gears 140 upon their inner ends and engaged with the bevel gears 138 to be operated by the latter. The shafts 139 extend through the vertical portion 137 of the chute and have their free ends mounted in the upper ends of the standards 141 mounted upon the main frame member 49. Each shaft 139 has a can lifting wheel 136

142 mounted thereon and each can righting wheel comprises a hub 143 with curved spokes 144 projecting radially therefrom. As the shafts 139 are properly spaced from 5 one another and rotated toward one another, each can, as it is raised by the wheel 135 and dropped upon the can righting wheels 142, owing to the fact that the length of the can is less than the distance between the can 10 righting wheels, will be engaged by the curved spokes 144 of the can righting wheels and one spoke of the wheel at the open end of the can will enter the can and turn the same to upright position, thereby righting 15 the can and causing the same to drop down the reduced and tapered portion 137 of the chute until its closed or lower end rests upon the portion of the chain 50 traveling upon the lower open extremity of the chute, it 20 being understood that the chute is properly supported above the forward end of the main frame member 49 by suitable standards 145. It will be understood that the front of the lower portion of the chute 137 is provided 25 with a suitable opening 146 to allow the can 25 to move out of the chute and travel with the chain 50 upon the main frame member 49, it being understood that the can 25 is engaged by one of the fingers 56 projecting 30 from the chain 50.

The shaft 134 is rotated by means of a suitable gear 147 mounted upon the short shaft 148 and engaged with the bevel gear 149 upon an extended end of the shaft 143. 35 The shaft 148 is rotated by means of a sleeve 150 which is engaged over one end of the shaft 148 and also over one end of the shaft 151 which has the bevel gear 152 mounted upon its lower end and engaged with the 40 bevel gear 153 mounted upon the end of the shaft 54. The sleeve 150 is slidably mounted upon the upper and lower ends of the shafts 148 and 151 respectively, and has diametrically opposite elongated slots 154 in 45 its upper end to accommodate the opposite ends of a pin 155, extending transversely through the shaft 148 while the lower end of the sleeve 150 is provided with the notches or recesses 156 in its lower end to receive 50 the lugs 157 carried by the shaft 151. It will be seen that when this sleeve is in its lowermost position the shaft 148 will be rotated upon rotation of the shaft 151. When the sleeve 150 is raised, however, to disengage the notches 156 from the lugs 157, rotation of the shaft 151 will have no effect 55 upon the sleeve 150 and shaft 148. The sleeve 150 may be readily raised by means of the lever 158 pivoted, as shown at 159, to 60 the collar 160, which latter is loosely engaged around the reduced central portion 161 of the sleeve, the lever being fulcrumed to the frame, as shown at 162.

It will be understood that the latch dog 65 29 is jointed intermediate of its ends, as

shown at 163 to allow the rear end of said dog to be raised by the pony jack 32, as previously described. It will also be understood that the roller 164 on the opposite end of the latch dog is normally retained in engagement with the cam wheel 30 by means of the coil spring 165 and that the shaft 31 upon which the cam wheel 30 is mounted is continually operated by means of the belt 166 which is connected in any suitable manner to the power shaft 91. It will further be understood that the cans 25 are retained in upright position and prevented from falling off of the chain 50 during movement of the latter, by means of the guide rails 167 to 80 opposite sides of the main frame member 49 and above the latter, said guide rails 167 being held in position by the short supporting uprights 168 having their lower ends secured to the opposite sides of the main 85 frame member 49.

The poise or weight 41 is slidably engaged upon the horizontal arm of the equalizer bar 40, said poise having spaced upper fingers 169 with a slot 170 therebetween and a 90 lower finger 171. The fingers 169 and 171 are engaged around the horizontal arm of the equalizer bar 40 and the poise or weight 41 carries the plate 172 resting in the lower finger 171 and provided with teeth upon its 95 upper face for engagement with the teeth 173 upon the lower face of the horizontal arm of the equalizer bar to retain the poise or weight in adjusted position. It will be understood that the front face of the horizontal arm of the equalizer bar is provided with suitable markings 174 in order that the poise or weight 41 may be readily and accurately adjusted. The poise or weight 41 is locked in adjusted position by means of 100 the wing nut 175 engaged upon the threaded upper end of the upwardly directed rod 176 projecting from the rear edge of the plate 172 and preferably formed with the same, the threaded upper portion of the rod 176 110 extending upwardly through the slot 170 and the wing nut, when tightened, bearing upon the upper face of the poise or weight 41.

It will be understood that the sleeve 75 115 and parts carried thereby are resiliently retained in normal position by the coil spring 75' having one end connected with the sleeve while its opposite end is suitably connected with the framework. It will also be understood that the clutch and operating mechanism for locking the friction wheel 96 for rotation with the shaft 94 are similar to the clutch and operating mechanism for locking the friction wheel 84 for rotation with the 120 shaft 82 and clearly illustrated in Fig. 12. Therefore these parts have not been shown in detail in a separate view. While any suitable electrical connections may be formed between the contact plates 60 and 61 and 125 130

the bars 73 and 76, I have shown two magnets 177 and 178 positioned respectively adjacent the free ends of the bars 73 and 106 for attracting these bars when the contact plates 58 and 59 carried by the equalizer bar 40 are properly engaged with the respective contact plates 60 and 61 carried by the U-shaped guide member 38', as previously described. It will be understood that 5 a battery 179 is provided and suitable conducting wires 180 provided to form electrical connections between the magnets 177 and 178, contact plates 60, 61, 58 and 59, and the battery 179. It will be evident that any 10 suitable electrical connections may be provided between the contact plates and the bars 73 and 106.

It is believed that the operation of the 15 device will be readily understood from the foregoing taken in connection with the accompanying drawings and therefore an extended explanation of the operation is deemed unnecessary. The operation will be briefly stated as follows: The cans 25 are 20 placed in the chute 132 and will be separated and raised, one at a time, by the can separating and raising wheel 135 and deposited upon the curved spokes of the can righting wheels 142 and as these wheels are 25 continually rotated toward one another, each can deposited upon the same will be turned 30 to upright position and its closed end deposited upon the traveling endless chain 50. One of the can engaging fingers 56 will engage 35 the can and cause the same to move with the chain 50 until it reaches the table 36. As the can passes over the forward 40 edge of the table, it passes between the trigger bars 35 and 70 and thereby separates said trigger bars. As previously described, 45 outward movement of the trigger bar 35 will operate the mechanism supporting the free end of the horizontal arm of the equalizer bar 40 and allow the latter to swing to its lowermost position. This movement of 50 the equalizer bar 40 forces the table 36 with the can upon the same upwardly and engages the upper open end of the can with the reduced lower end of the spout 18. As 55 the equalizer bar 40 reaches its lowermost position, the engagement of the contact plate 59 with the contact plate 61 turns the sleeve 103 through the electrical connections previously described, and disengages the clutch member 81 from the clutch member 83, and engages the clutch member 98 with the clutch member 97, thereby causing operation 60 of the feed screw 15 to feed the sauer kraut or other material to the raised can. The outer movement of the trigger bar 35 also operates the pony jack 32 as previously described to cause the latch dog 29 to open the valve 23. After a predetermined amount of sauer kraut or other material has been 65 fed to the can 25, the weight of the material

70 together with the weight of the can will force the can and table 36 downwardly, returning the equalizer bar to its uppermost position, thereby disengaging the contact plate 59 from the contact plate 61 and engage 75 the contact plate 58 with the contact plate 60, thereby breaking one circuit and closing another to allow the magnet 177 to draw the bar 73 forwardly and thereby engage 80 the clutch member 81 with the clutch member 83 to cause the chain 50 to again move and carry the filled can away from the table 36 and bring the next can into position to be filled in the same manner as the can or cans ahead of the same. This return movement of the equalizer bar 40 and engagement of the contact plate 58 with the contact plate 60 also breaks the circuit with 85 which is connected the magnet 178 and thereby allows the arm 106 to be moved away from the magnet 178 and the sleeve 103 to rotate under action of the spring 101 and thereby disengage 90 the clutch members 97 and 98 and discontinue operation of the feed screw 15. It will be understood, however, that as each can is brought to position between the trigger bars 35 and 70, and then deposited upon the table 36, the same operation just described will take place, thereby filling the cans and carrying the 95 same to the rear end of the machine in turn. It will also be understood that when desired, any set of can feeding, righting, and filling mechanism may be thrown out of operation by raising the proper sleeve 150, as previously described.

While I have shown the preferred form 100 of my invention it will be understood that minor changes may be made in the details of construction and arrangements of the 105 various parts of the machine and I therefore do not wish to be limited to the specific construction and arrangement of parts as shown in the drawings and described in the specification.

As shown in Fig. 24, the sprocket wheel 122 is loosely mounted upon the shaft 12 and has formed therewith the clutch member 122' which is resiliently retained in engagement with the clutch member 187 by means 110 of the coil spring 188 bearing against the opposite face of the sprocket wheel 122, one end of said spring being engaged against the flange 189 formed on the outer extremity of the shaft 12, as clearly shown in the 115 drawings. It will be understood that the clutch member 187 is rigidly mounted upon the shaft 12 and owing to the fact that the clutch member 122' formed upon one face of the sprocket wheel 122 is resiliently retained in engagement with the clutch member 187, said clutch member 122' and sprocket wheel 122 will readily move outwardly and disengage from the clutch member 187 should the material become 120 125

clogged in the hoppers and operation of the turret 13 retarded or temporarily prevented, thereby eliminating all danger of breaking these parts.

What I claim is:—

5. 1. A machine of the character described comprising a main hopper, a lower feed hopper, an intermediate hopper, means in the main hopper for feeding material to the intermediate hopper, a spout carried by the feed hopper, feeding means in the feed hopper, means carried by the intermediate hopper for depositing material from the main hopper to the feeding means and preventing 15 clogging of the same, a table beneath the spout, a valve for the spout, means for placing a can upon the table, means for raising the table when a can is placed upon the same to present said can to the spout, means for 20 opening the valve and starting operation of the feeding means upon upward movement of the table, said table being adapted to move downwardly with its can after the same has been filled from the spout of the feed hopper, means for closing the valve, and means for stopping operation of the feeding means, and withdrawing the can upon return of the table to normal position.

2. A machine of the character described comprising a feed hopper, a spout depending from the said hopper, feeding means within said hopper and extending into the upper end of the spout, an endless can conveyer beneath the spout, means for feeding 30 cans to the conveyer, a table in the path of the can conveyer and beneath the spout, means for supporting the table, an equalizer bar connected with the table, latch mechanism for retaining the equalizer bar in its 35 uppermost position, means for stopping movement of the can conveyer as a can upon the same is brought to position above the table, means for releasing at this time the latch mechanism, and thereby allowing the 40 equalizer bar to drop and raise the table with the can upon the same to bring the can to the mouth of the spout, means for starting operation of the feeding means upon downward movement of the equalizer bar, 45 the table being adapted to be returned to its normal position by the weight of the material fed to the can, the downward movement of the table causing the equalizer bar to be returned to its uppermost position, means 50 whereby the return of the equalizer bar to its uppermost position will prevent further operation of the feed screw and again start operation of the can conveyer to withdraw the filled can from upon the table and bring 55 another can into position.

6. 3. A machine of the character described comprising a feed hopper, feeding means within the hopper, a spout at one end of the feed screw and having a reduced lower end, 60 a main frame member, a vertically movable

table within said frame member, a can conveyer adapted for movement over the tables to bring a can into position above the latter, an equalizer bar connected with the table, means for retaining the equalizer bar 70 in inoperative position, a valve for the spout, a dog for operating the valve, said dog being normally out of engagement with the valve, a pair of trigger bars to either side of the can conveyer and adapted to be separated by a can brought therebetween by the conveyer as the can reaches the table, connections between the dog and trigger bars, connections between the trigger bars and the means for retaining the equalizer bar in 75 inoperative position, whereby as the can passes between the trigger bars the equalizer bar will be released and the dog will be thrown into position to engage the valve and open the latter, said equalizer bar when released 80 being adapted to move downwardly and raise the table to engage the can with the reduced end of the spout, means for operating the feeding means to feed material to the can while the latter is engaged with the 85 spout, said table and can being adapted to move downwardly after the latter has been filled and return the equalizer bar to normal position, and means for starting operation of the can conveyer to withdraw the 90 filled can and bring another into position upon return of the table to its lowermost position.

4. A machine of the character described comprising a feed hopper, a spout depending from the feed hopper, a table beneath the spout, a can conveyer movably engaged over the table, means for feeding cans to the conveyer, means for righting each can as the same is fed to the conveyer, can engaging 100 fingers carried by the conveyer causing the cans to move with said conveyer, a main frame member, the table and conveyer being mounted in the main frame member, means for stopping operation of the conveyer as a 105 can upon the same is brought to position above the table, means for raising the table as a can is brought to position above the same to present the open end of the can to the feed spout, and means for filling the can 110 from the spout of the hopper, said can and table being adapted to be caused to move downwardly by the weight of the material and can after the latter has been filled, the 115 downward movement of the table causing the conveyer to again operate to withdraw the filled can and bring another into position.

5. A machine of the character described comprising a main hopper and a feed hopper, means for supplying material to the feed hopper from the main hopper, means for returning to the main hopper any excessive amount of material deposited upon the means for supplying material to the feed 125 130

- hopper and thereby preventing clogging of the feed hopper, a spout for the feed hopper, a can conveyer beneath the feed hopper, a table beneath the spout and in the path of the can conveyer, means for operating the can conveyer, means for feeding cans to the can conveyer, guide rails for the cans, said conveyer being adapted to deposit the cans in succession upon the table, means for causing upward movement of the table and stopping operation of the conveyer operating means when a can is placed upon the table, the upward movement of the table causing the upper end of the can to engage with the spout, means for opening the spout and feeding material from the feed hopper to the can by way of the spout when said can is engaged therewith, the table being adapted to move downwardly with the can when the latter is filled, and means for again throwing into operation the conveyer operating means and closing the spout when the can and table return to normal position.
6. A machine of the character described comprising a supporting framework, an endless can conveyer mounted in said framework, means for feeding cans to one end of the endless conveyer, a plate positioned in the path of the endless conveyer, an equalizer bar connected with said plate, means for locking the equalizer bar in its uppermost position whereby the plate will be normally retained in its lowermost position, a hopper above said plate, a spout depending from said hopper, a valve for said spout, said conveyer being adapted to deposit the cans in succession upon the plate, can guiding means above and to either side of the plate, con-

nctions between the equalizer bar locking means and the can guiding means, whereby the equalizer bar will be released as a can travels between the can guiding means, the weight of the released equalizer bar causing the latter to drop and raise the plate and thereby engage the can upon the latter with the spout, and means for controlling the valve of said spout.

7. A machine of the character described comprising a supporting framework, an endless conveyer within said framework, means for feeding cans to one end of the endless conveyer, means for righting said cans, a can receiving and raising plate in the path of said conveyer, an equalizer bar connected with said plate, a can guiding means to either side of said plate and mounted on the framework, means for locking the equalizer bar in its uppermost position, means for operating the endless conveyer, a hopper above the plate, a spout for said hopper, a valve for said spout, operating means for said valve, connections between the can guiding means and the means for locking the equalizer bar in its uppermost position, connections between said can guiding means and the valve operating means, and connections between the opposite portion of the can guiding means and the conveyer operating means.

In testimony whereof I hereunto affix my signature in the presence of two witnesses.

FRANK M. WRIGHT.
